(**) Term: **14 Years**

(57) **CLAIM**

(21) Appl. No.: **29/306,585**

The ornamental design for package for a lock product, as shown and described.

(22) Filed: **Apr. 11, 2008**

DESCRIPTION

(30) **Foreign Application Priority Data**

Jan. 4, 2008 (TW) 97300086

FIG. 1 is a perspective view of package for a lock product showing my new design;

(51) **LOC (9) Cl.** **09-07**

FIG. 2 is a front elevational view thereof;

(52) **U.S. Cl.** **D9/455; D9/424; D9/415**

FIG. 3 is a rear elevational view thereof;

(58) **Field of Classification Search** D9/717,

FIG. 4 is a left side elevational view thereof;

D9/709, 704, 670, 660, 658, 652, 646, 632,
D9/605, 604, 601, 457, 454, 453, 451, 441,
D9/439, 436, 434, 424, 415; D5/61, 60,
D5/58; D3/303, 276; D20/28, 42; D14/492,
D14/489; D11/221; 53/133.4; 383/64, 61.2,
383/5; 206/470, 469, 468, 462; 220/212;
222/78

FIG. 5 is a right side elevational view thereof;

See application file for complete search history.

FIG. 6 is a top plan view thereof;

(56) **References Cited**

FIG. 7 is a bottom plan view thereof;

U.S. PATENT DOCUMENTS

FIG. 8 is a perspective view of the second embodiment of package for a lock product;

D278,974 S * 5/1985 Ray D9/704
